**POWER DRIVEN RAZOR HAIR CUTTING
 AND SHAPING APPARATUS**
 Norman Cassella, 477 Riverside Ave.,
 Rutherford, N.J. 07070
 Filed Dec. 20, 1966, Ser. No. 603,243
 6 Claims. (Cl. 30—272)

My invention relates to a power driven razor hair cutting device or power driven shaper utilizing a razor type 10 blade assembly providing a slicing action.

The increasing popularity of men's hair styling has created a whole new field of specialized techniques in the cutting of men's hair. Razor cutting is one of these techniques.

At the present time the technique used is to razor cut the hair manually, using a conventional barber's straight razor. The most successful method is to use a slicing stroke with the razor while holding the hair with a comb.

Most hair stylists have some form of electric motor driven units to drive a variety of clipper blades. It would therefore be most desirable to provide a mechanism readily attachable to and fit this type of drive unit. Such units drive the cutting mechanism from side to side cutting the hair between a plurality of cooperating teeth.

In accordance with my invention, I provide a frame, one end of which is formed to be removably attached to a conventional electric power driven clipper drive unit. The frame has ways or slots for slidably receiving the supporting extensions of the carriage which in turn receives a replaceable razor blade assembly. The carriage is connected by means of a connecting link to an oscillating bell crank mounted on the frame and operatively linked with the driving unit when the cutting mechanism is attached to the drive unit. A comb member is detachably secured to one side of the frame and is designed so that the blade rides tightly against the comb. A cover is detachably secured to the other side of the frame. The blade may be quickly replaced by removing the comb. In a modification I dispense with the carriage and drive the blade assembly directly from the bell crank and link. The driving unit could be made an integral part of the whole assembly.

Referring to the drawings:

FIGURE 1 is a top or plan view of a device or mechanism made according to my invention;

FIGURE 2 is a view of FIGURE 1 with the cover, comb and the blade removed;

FIGURE 3 is a side view of FIGURE 1;

FIGURE 4 is a bottom view of FIGURE 1;

FIGURE 5 is a bottom view of FIGURE 1 with the comb removed;

FIGURE 6 is a partial view of the frame showing the details of the attaching structure;

FIGURE 7 is a section taken along the line 7—7 of FIGURE 1;

FIGURE 8 is an enlarged section taken along the line 8—8 of FIGURE 1;

FIGURE 9 shows the mechanism partially disassembled and laid out;

FIGURE 10 shows details of the carriage and blade;

FIGURE 11 is a top or plan view of a modification of the device shown in FIGURE 1;

FIGURE 12 is a view similar to FIGURE 11 with the cover removed;

FIGURE 13 is a side view of FIGURE 11;

FIGURE 14 is a bottom view of FIGURE 11;

FIGURE 15 is similar to FIGURE 14 but with the comb removed;

FIGURE 16 shows the blade used; and

FIGURE 17 is a section taken along the line 17—17 of FIGURE 11.

Referring to FIGURES 1 to 5 and FIGURE 9, a hair

2

cutting apparatus made according to my invention includes a frame 20, having a portion 21 formed to be attached at a proper angle to a conventional power operated clipper driving mechanism, the member 22 providing the engaging structure. The frame 20 is provided with the grooved ways 23 and 24.

A reciprocating carriage 25 is provided with extensions or arms 26 and 27 slidably received within the ways 23 and 24 for supporting the carriage 25 in the frame 20. The carriage is also provided with an arm or extension 28 which is connected by a link 29 pivotally connected to extension 28 and the bell crank 30 pivotally mounted at 30' on frame 20. The bell crank 30 is provided with ears or extensions 31 and 32 which are engaged by the vibrating arm or armature (not shown) on the drive unit when the apparatus or mechanism is mounted on the drive unit. In operation the carriage reciprocates longitudinally of the frame.

The carriage is provided with a recess 33 (FIGURES 20 8 and 10) which snugly receives and retains the conventional disposable blade 34 having the head 35 which fits into recess 33.

When attached to the electrically driven power unit, the bell crank 30 is oscillated about its pivot 30'. This action is transmitted through link 29 to carriage 25 to cause a rapid reciprocating action of the carriage 25 and blade 34 to cause a slicing action.

Removably secured to frame 20 is the comb 36, having a recess 37 for receiving the head 35 of the blade. The relationship of the blade and comb is such that there is a very tight sliding contact between the blade and comb. I have found that this is necessary to prevent hair from accumulating between the blade and comb which accumulation I have found to interfere with proper cutting. The length of the teeth of the comb also must not be too long since long teeth permit only small amounts of hair to be cut. The blade 25 can be easily replaced by removing the comb 36.

A cover 38 is secured to the other side of the frame 40 holding the carriage in place on the frame.

In a modification of my invention shown in FIGURES 11 to 17, inclusive, I am able to dispense with the carriage and the cover and still use a conventional razor blade.

The frame 40 is provided with the slots or ways 41 and 42 which slidably receive the head or backing 43 of the blade 44. The blade is provided with a link hole or aperture 45, into which is pivotally fitted one end of the link 46, the other end of the link 46, being pivotally received in the bell crank 47 having arms 48, 49 which engage the operating vibrating tongue of the driving unit.

A comb 50 is detachably secured to frame 40.

In this modification the blade 44 is reciprocated in the same manner as described for the embodiment shown in FIGURES 1 to 10, inclusive.

What is claimed is:

1. A power driven razor hair cutter comprising
  - (a) an elongated U-shaped frame having slot structure therein and having a head portion for attachment to a power driven unit,
  - (b) a detachable comb member secured to said frame and having a slot structure registering with the slot structure in said frame,
  - (c) a blade assembly having a portion slidably mounted in said slot structures,
  - (d) a bell crank pivotally mounted at one end of said frame and having means for co-acting with a power driven unit,
  - (e) and link means connecting said blade assembly and said bell crank whereby when said bell crank is oscillated said blade assembly will be reciprocated across said comb.

2. A power driven razor hair cutter comprising
- (a) an elongated U-shaped frame having slots in the legs thereof and having a head portion for attachment to a power driven unit,
  - (b) a detachable comb member secured to said frame and having a slot structure registering with the slots in said frame, 5
  - (c) a carriage slidably mounted on said frame and having extensions received within said slots and said slot structure,
  - (d) a blade assembly mounted in said carriage, 10
  - (e) a bell crank pivotally mounted at one end of said frame and having means for co-acting with a power driven unit,
  - (f) and link means connecting said carriage and said bell crank whereby when said bell crank is oscillated by said power driven unit said carriage and blade assembly will be reciprocated. 15
3. A power driven razor hair cutter comprising
- (a) an elongated U-shaped frame having slots in the legs thereof and having a head portion for attachment to a power driven unit, 20
  - (b) a detachable comb member secured to said frame and having a slot structure registering with the slots in said frame,
  - (c) a carriage having extensions received within said slots and slot structure, 25
  - (d) a blade mounted on said carriage,
  - (e) a bell crank pivotally mounted at one end of said frame and having means for co-acting with a power driven unit, 30
  - (f) link means connecting said carriage and said bell crank whereby when said bell crank is caused to oscillate said carriage and blade will be reciprocated,
  - (g) and said blade being in slidable contact with said comb. 35
4. A power driven razor hair cutter comprising
- (a) an elongated U-shaped frame having slots in the legs thereof and having a head portion for attachment to a power driven unit,
  - (b) a detachable comb member secured to said frame and having a slot structure registering with the slots in said frame, 40
  - (c) a blade assembly slidably mounted in said slots and slot structure,
  - (d) a bell crank pivotally mounted at one end of said frame and having means for co-acting with a power driven unit,
  - (e) and link means connecting said blade assembly and said bell crank whereby when said bell crank is oscillated said blade assembly will be reciprocated, said blade assembly having a close slidable contact with 45

- 4
- said comb member, said comb member retaining said blade assembly in said frame.
5. A power driven razor hair cutter comprising
- (a) an elongated U-shaped frame having slots in the legs thereof and having a head portion for attachment to a power driven unit,
  - (b) a detachable comb member secured to said frame and having a slot structure registering with the slots in said frame,
  - (c) a carriage slidably mounted on said frame and having extensions received within said slots, 10
  - (d) a blade assembly mounted in said carriage,
  - (e) a bell crank pivotally mounted at one end of said frame and having means for co-acting with a power driven unit,
  - (f) and link means connecting said carriage and said bell crank whereby when said bell crank is oscillated said carriage and blade assembly will be reciprocated, said blade assembly having a close slidable contact with said comb member, said comb member retaining said blade assembly in said carriage and permitting ready replacement of said blade when said comb member is removed. 15
6. A power driven razor hair cutter comprising
- (a) an elongated U-shaped frame having slots in the legs thereof and having a head portion for attachment to a power driven unit,
  - (b) a detachable comb member secured to said frame and having a slot structure registering with the slots in said frame,
  - (c) a blade assembly slidably mounted in said slots and slot structure, 20
  - (d) a bell crank pivotally mounted at one end of said frame and having means for co-acting with a power driven unit,
  - (e) and link means connecting said blade assembly and said bell crank whereby when said bell crank is oscillated said blade assembly will be reciprocated, said blade assembly having a close slidable contact with said comb member, said comb member retaining said blade assembly in said frame and permitting ready replacement of said blade when said comb member is removed. 25
